(57) **CLAIM**

The ornamental design for a camera housing, as shown and described.

DESCRIPTION

FIG. 1 is a front, top and right side perspective view of a camera housing showing my new design;
FIG. 2 is a front elevational view the camera housing.
FIG. 3 is a rear elevational view the camera housing.
FIG. 4 is a left side elevation view of the camera housing.
FIG. 5 is a right side elevation view of the camera housing.
FIG. 6 is a top plan view of the camera housing.
FIG. 7 is a bottom plan view of the camera housing; and,
FIG. 8 is a front, top and left side perspective view of the camera housing shown in a state of use.
The broken line portions of the camera housing in FIG. 8 are shown to illustrate environmental support structure and form no part of the claimed design.
